UNITED STATES PATENT OFFICE

159,178

AUTOMOBILE HEADLIGHT

Alfred F. Vlautin, San Francisco, Calif.

Application August 2, 1949, Serial No. 4,242

Term of patent 3½ years

(Cl. D48—32)

To all whom it may concern:

Be it known that I, Alfred F. Vlautin, a citizen of the United States of America, residing at San Francisco, in the county of San Francisco and State of California, have invented a new, original, and ornamental Design for an Automobile Headlight, of which the following is a specification, reference being had to the accompanying drawing, forming a part thereof.

Fig. 1 is a perspective view of an automobile headlight showing my new design, and

Fig. 2 is a side elevational view of the same.

The dotted lines shown in the drawing are for illustrative purposes only.

I claim:

The ornamental design for an automobile headlight, substantially as shown and described.

ALFRED F. VLAUTIN.
